HEATING PLANT

Oscar H. Dicke, Rochester, N. Y.

Application November 21, 1941, Serial No. 419,839

3 Claims. (Cl. 183—32)

This invention relates to improvements in heating plants, particularly to such plants of the hot air type in which a blower is employed at times to promote circulation of the air from the furnace to the space to be heated and the return of air therefrom to the furnace.

In such heating plants it is frequently desired to employ a filter, a humidifying device, and/or other devices to filter and/or humidify the air. Such devices, particularly filters, create substantial resistance to the flow of the air. If therefore, in such a plant, the blower is not operating, the resistance to air flow is so great that circulation by convection is impossible. If a by-pass is provided around the filter so that circulation by convection can be obtained when the blower is not operating it is customary to provide a valve or damper of some kind which must be open when natural drafts or convection circulation is desired but which must be closed when the blower is in operation to prevent the air delivered by the blower from being driven in the reverse direction through the cold air return duct into the apartment. Such valves or dampers and the necessary means for operating them add to the cost of the installation and of operation and increase the cost of maintenance.

It is an object of the present invention to provide an improved heating plant comprising a furnace, hot air distribution conduits, a cold air return conduit, a filter or other air conditioning device and a blower, and a by-pass around the blower and filter, the parts being so arranged that the air delivered by the blower creates an injector effect which tends to draw air through the by-pass in the direction toward the furnace when the blower is in operation so that it is not possible for air to be blown in a reverse direction through the by-pass and the cold air return into the apartment.

Another object is to provide such a device in which the parts are so arranged and proportioned that a minimum amount of air or no air at all is drawn through the by-pass by injector action when the blower is in operation so that all or substantially all of the air being circulated must pass through the filter or other air conditioning device.

These and other objects will become apparent from the following description taken in connection with the attached drawings showing several illustrative embodiments of the invention and wherein:

Fig. 1 shows more or less schematically and

partly in section a heating plant embodying the invention;

Fig. 2 is a partial partly sectional view taken along the line 2—2 of Fig. 1 looking in the direction of the arrows;

Fig. 3 shows a side view partly in section of a modification;

Fig. 4 is a plan view partly in section of the form of device shown in Fig. 3; and

Fig. 5 is a cross-sectional view taken on the line 5—5 of Fig. 3 looking in the direction of the arrows.

Referring to said drawings, the numeral 11 represents generally a hot air furnace which may be of conventional construction provided with a flue pipe 12, an air intake or draft damper 13, and a check damper 14. Such furnaces usually have a fire pot such as 15 and are surrounded by a casing such as 16 and usually have a return air conduit such as 17. As usual, one or more hot air conduits 18 lead from the upper part of the furnace casing or bonnet to the various rooms to be heated, the air entering the room through registers such as 19. The numeral 20 indicates such a room.

The numeral 21 indicates a cold air return grate connecting to a cold air return conduit such as 22. In the form shown, the lower part of this conduit is completely closed by one or more filter slabs, such as 23, thus providing a space 24 in which is housed a blower 25 driven by an electric motor 26 by means of the belt 27. One or both ends of said blower are open to take in air from the space 24.

As shown, a by-pass conduit 28 is provided leading from the cold air return duct 22 and connecting with the conduit 17. The by-pass 28 connects with the duct 17, although it is also possible to have it connect directly to the room space 20. 29 indicates an injector plate preferably pivoted as at 30 and held in the desired position of adjustment by any suitable means such as bolts 31.

The operation of the device is as follows: when the blower is operating it delivers air at a substantial velocity through the throat formed under the injector plate 29. At this point the cross-sectional area is substantially reduced so that the velocity of flow is substantially increased. Therefore, in accordance with Bernoulli's law, pressure at this point is very substantially reduced preferably even slightly below atmospheric pressure so that there is no pressure available to drive air upwardly through the by-pass 28 and, in fact, a

certain small amount of air is probably usually drawn downwardly through by-pass 28. Beyond the throat the cross-sectional area of the passage increases substantially. This results in a reduction in velocity and a large part of the kinetic energy of velocity will, in accordance with Bernoulli's law be converted into potential energy, resulting in an increase in pressure as the air enters the bottom of the furnace casting, producing the desired pressure for causing circulation.

It will be noted that when the blower is not in operation there is a clear path around the filter through the passage 28 so that natural convection will take place while the blower is not in operation so that heat is being carried from the furnace into the room even while the blower is not operating, resulting in even room temperature.

Any desired means may be employed for controlling the operation of the blower driving motor 25, such as a hand operated switch. In Fig. 1 is shown one manner of control which may in some cases be desirable, comprising a thermostat 33 in the room to be heated and a thermostat 34 in the bonnet of the furnace. The conductor 33 is connected from a source of electric supply and to the thermostat 34 from which the conductor 35 leads to the motor 25 from which the conductor 36 leads to the thermostat 37 from which the conductor 38 leads to the source of power supply. The thermostat 37 is preferably so arranged as to close the circuit whenever the room temperature drops below a certain point, say 70° F., and the thermostat 34 is so arranged as to open the circuit when the bonnet temperature is below a predetermined temperature, such as 100° F. It will be seen therefore that whenever the temperature in the room is below 70° and the temperature in the bonnet is above 100°, the blower will be operated. If, however, the room temperature rises to 70° or if the bonnet temperature falls below 100° F., the motor and blower will not operate. This is to prevent on the one hand excessive heating of the room and on the other hand to prevent the circulation of cold air. In heating plants of this type there is usually also a thermostatically operated device for controlling the dampers such as 13 and 14, or if an oil burner or stoker is used, suitable means for controlling the operation thereof. If such a regulating device is employed, the thermostat 37 would usually control said device, which device would in turn control a switch between the conductors 36 and 38 so that the blower could operate only when the thermostat calls for heat. Such a system has however not been shown because it does not form a part of the present invention which will be useful in any forced fluid circulation system in which some means are provided to cause intermittent operation of the blower or other fluid pump.

In the modified form shown in Figs. 3, 4 and 5 the corresponding parts have been designated by the same numerals as those employed in Figs. 1 and 2, the subscript "a" being added. The principal difference in construction is that in this case a separate housing 40 is employed which contains the blower or may comprise the housing of the blower itself, the top of which is closed by the filter members 21a. The housing is smaller than the enclosing casing of conduit 22a so as to provide a by-pass passage around all sides of housing 40. Said housing 40 is gradually contracted and terminates in a nozzle portion 41

substantially in line with the narrowest portion 17b of the passage 17a. In this way, an even more accentuated injector effect can be secured.

It will be noted that the constructions shown and described will serve admirably to accomplish the objects stated above. It is to be understood, however, that the constructions disclosed above are intended merely as illustrative of the invention and not as limiting as various other modifications therein may be made without departing from the invention as defined by a proper interpretation of the claims which follow.

I claim:

1. In a combined forced draft and natural draft air circulator for hot air heating systems employing hot air furnaces comprising: a box-like main casing terminating in a conduit having a narrow neck near said casing and flaring out to a larger cross-sectional area toward its free end, which free end may be connected into the lower end of such furnace; said casing having an opening which may be connected with a cold air return conduit of said system; an intermittently operated blower in said main casing consisting of a second casing having an inlet opening and having an outlet opening terminating substantially in the neck of said conduit but of a smaller cross-sectional area than said neck, and of a fan in said second casing which when operated draws air through said inlet opening and projects it through said outlet opening into said conduit; and a filter located to filter only the air passing through said inlet opening of said second casing; whereby when said blower is operating the inertia of the stream of blower propelled filtered air as it spreads during its passage through said conduit and toward said furnace causes a partial vacuum to be created about said stream in said conduit which vacuum tends to draw unfiltered air through the by-pass formed between said outer casing and said second casing into said conduit and whereby unfiltered gravitationally propelled air may flow freely through said by-pass when said fan is not operating.
2. In a heating plant, a furnace for heating air to be circulated to the space to be heated, an intermittently operating blower including a housing having an inlet and an outlet opening, a filter located so as to filter only the air passing through said housing, a conduit of gradually increasing cross-sectional area extending from said outlet opening to the furnace, at least one hot air conduit extending from the furnace to the space to be heated, a cold air conduit connecting from said space to said inlet opening and a by-pass connecting from said cold air conduit to said first mentioned conduit and around said housing and filter, the said first mentioned conduit having a restricted cross-sectional area near said housing where said by-pass joins it followed by said gradually increasing cross-sectional area, so that the air flowing through said housing and filter tends to draw air through said by-pass toward the furnace, whereby when the blower is not operating air may be drawn from said space to the furnace through said cold air conduit said by-pass and said first mentioned conduit by convection.
3. In a combined forced draft and natural draft air circulator for a hot air heating system employing a hot air furnace comprising: an intermittently operating blower including a housing having an inlet opening and an outlet open-

ing, a conduit structure of gradually increasing cross-sectional area extending from said outlet opening to such furnace and having its most restricted cross-sectional portion where it joins said outlet opening, a by-pass in multiple with said blower housing and extending from said inlet opening to join said conduit structure at its most restricted cross-sectional portion, a filter located so as to filter the air passing through said inlet opening but not the air passing through said by-pass, whereby when said blower is operating the inertia of the stream of blower pro-

pelled air as it spreads during its passage through said conduit structure and toward such furnace causes a partial vacuum to be created about said stream near said most restricted portion in said conduit structure which vacuum tends to draw unfiltered air through said by-pass and into said conduit structure and whereby due to the heat of such furnace gravitationally propelled unfiltered air may flow freely through said by-pass and conduit structure to such furnace when said blower is not operating.

OSCAR H. DICKE.
